UNITED STATES PATENT OFFICE.

JOHN DAVID LANDERS AND GUSTAVUS JOHNSON, OF WINNIPEG, MANITOBA, CANADA.

LAMP.

No. 914,148.

Specification of Letters Patent.

Patented March 2, 1909.

Application filed October 16, 1907. Serial No. 397,671.

To all whom it may concern:

Be it known that we, JOHN DAVID LANDERS and GUSTAVUS JOHNSON, both of the city of Winnipeg, in the Province of Manitoba, Canada, have jointly invented certain new and useful Improvements in Lamps, of which the following is the specification.

Our invention relates to improvements in lamps, and the object of the invention is to provide an improved construction in devices for heating signal or heavy oils in lamps and lanterns by means of the lamp flame, and it consists essentially of a looped hollow tube secured to the burner, a continuous metallic loop surrounding the flame, and in a plane at right angles thereto, and means for allowing for circulation through the tube, all arranged and constructed as hereinafter more particularly described.

Figure 1 is a perspective view of a flat wick lamp burner, provided with our invention. Fig. 2 is a plan view of the burner and the attachment, as in Fig. 1. Fig. 3 is a vertical sectional view, the section being taken in a plane denoted by the line $X-X'$ in Fig. 2. Fig. 4 is an enlarged, detailed, perspective view of the caps secured to the tube.

In the drawings like letters of reference indicate corresponding parts in each figure. A represents the wick tube of a burner, and B the screw cap, in which the aforesaid tube is secured.

C is a metallic wire loop, and D is a hollow metallic tube in the form of a loop, and having its free ends D^1 D^2 extending upwardly through the screw cap B. The wire C envelops the base of the flame, extending in a loop, substantially in a plane at right angles to the flame. The free ends of the wire C^1 C^2 pass downwardly practically at right angles to the plane of the loop, and extend into the open end D^2 of the tube D. It will be noted, referring to Fig. 3, that the end C^2 extends well into the tube, and that the end C^1 is shorter, and does not extend below the upper face of the screw cap. This allows that a continuous air passage may be had throughout the tube, opening at one end at E, above the face of the burner (the extending end C^2 does not fill the tube). The other end of the tube has an opening E^1 above the face of the screw cap, and the end of the tube is other-

wise closed. It will be understood that the extending ends of the wire C make a tight joint with the tube, so that no air has access to the tube, except through the opening E.

We are aware that various forms of heating wires have heretofore been used, and that such have a wire loop extending into or enveloping the flame, and have one of the ends of the loop extending downwardly into the wick. However in these forms, considerable time is taken to heat the wire throughout its length and they are also subject to excess of heat. In the form which we employ the tube is necessarily of larger circumference than the wire, and in this way there is an enlarged radiating surface to the oil of the lamp. Further the extending ends of the wire C, within the tube, primarily heat the air within the tube. This causes a circulation through the tube loop, the heated air surrounding the wick tube passing inwardly through the opening E^1 , and outwardly through the opening E owing to the end D^2 being raised to a higher temperature than the end D^1 . In this way the complete interior of the tube D is quickly heated, as the heated air circulates freely throughout its entire length, and the heat is continuously more or less uniform.

If it be found in practice that the openings E E^1 in the tube are easily filled or clogged, such may be done away with by having a hole F^2 at the end of the tube, and placing a cap F (Fig. 4) over the opening. A lip F^1 could be placed over the opening E.

What we claim as our invention is:

1. In a device of the class described the combination with a wick tube and burner cap, of a hollow looped tube extending downwardly from the cap, one end of said tube being closed and having a perforation therein above the top of the burner cap, a heating wire loop above the wick tube and in a plane at right angles thereto, the said loop having its free ends passing downwardly into the open end of the looped tube, as and for the purpose specified.

2. In a device of the class described the combination with a wick tube and a burner cap, of a looped hollow tube extending downwardly from the burner cap and having one of its ends closed, a heating wire loop

above the wick tube and in a plane at right angles thereto, the said wire having one of its ends extending down into the open end of the tube to a point below the top of the burner cap, and the other end extending into the tube above the top of the burner cap, the said tube having an opening therein below said last named end of the heating wire and above the top of the burner cap, and the 10 closed end of said tube having a perforation

above the burner cap, as and for the purpose specified.

Signed at Winnipeg, in the Province of Manitoba, this 7th day of Septr. 1907.

JOHN DAVID LANDERS.
GUSTAVUS JOHNSON.
